[57] **CLAIM**

The ornamental design for free-standing heating stove, substantially as shown and described.

DESCRIPTION

FIG. 1 is a front elevational view of a free standing heating stove, showing my new design;

FIG. 2 is a rear elevational view thereof;

FIG. 3 is a right side elevational view, the left side being a mirror image thereof;

FIG. 4 is a top plan view thereof;

FIG. 5 is a bottom plan view thereof;

FIG. 6 is a front elevational view of a second embodiment of a free standing heating stove, wherein the only difference resides in the use of figured, cast iron door panels.

FIG. 4FIG. 5FIG. 6
